JOHN S. O'LEARY, OF PHILADELPHIA, PENNSYLVANIA

NEEDLE GUIDE FOR RECORDS

Application filed December 6, 1929. Serial No. 412,185.

This invention relates to improvements in phonographic records, and has as one of its objects to overcome one of the disadvantages attending the starting of a phonograph, namely, that the stylus of the reproducer is sometimes unintentionally or accidentally dropped into the record groove of the disk at a point more or less in advance of the starting end of the groove, and therefore the present invention contemplates the provision of a phonograph record having means whereby the stylus will be automatically directed to the starting end of the record groove even though it should be carelessly lowered onto the record.

This invention also consists in certain other features of construction and in the combination and arrangement of the several parts to be hereinafter fully described, illustrated in the accompanying drawings, and specifically pointed out in the appended claim.

In describing my invention in detail, reference will be had to the accompanying drawings wherein like characters denote like or corresponding parts throughout the several views, and in which:—

Figure 1 is a plan view of a disk record embodying the invention.

Figure 2 is a detail sectional view, on an enlarged scale, on the line 2—2 of Figure 1 looking in the direction indicated by the arrows.

Figure 3 is a view showing how the guide grooves merge with one another and the sound groove.

The record disk is indicated by the numeral 1 and is provided upon one or both of its faces with the usual record groove which is indicated by the numeral 2.

In carrying out the invention, the face of the record in which the record groove 2 is formed, is likewise formed with a plurality of stylus guiding grooves which are indicated in the drawings by the numeral 3, and these grooves are preferably of slightly greater depth than the groove 2 and, from a point somewhat in advance of the starting point of the groove 2, the grooves 3 are so arranged that they converge, on arcuate lines, to the starting end of the groove 2 and mutually

merge with one another near their point of juncture with the said end of the groove 2, so that when the stylus of the phonograph is lowered onto the record so that it will seat in any one of the grooves 3, and the record is rotated, the stylus will be guided accurately into the starting end of the groove 2. It will be observed by reference to Figure 1 that all of the grooves 3 are located within the bounds of the record groove 2.

From the foregoing it will be evident that as previously stated, even though the stylus should be lowered onto the record in a careless manner, so long as its point engages in one of the guiding grooves 3, the stylus will, in the continued rotation of the record enter the record groove precisely at the starting end thereof.

What I claim is:—

A phonographic record having, at the starting end of its sound record groove, a plurality of stylus guiding grooves located within the bounds of the record groove and in the same horizontal plane therewith, said guiding grooves leading to the said starting end of the sound record groove on arcuate lines eccentric to the axis of rotation of the said sound record groove, and having their inner ends merging with one another and with the said starting end of the sound record groove.

In testimony whereof I affix my signature.

JOHN S. O'LEARY.
